UNITED STATES PATENT OFFICE.

CHARLES R. KEERAN AND JOHN P. LYNN, OF CHICAGO, ILLINOIS, ASSIGNORS TO REALITE PENCIL MANUFACTURING COMPANY, OF CHICAGO, ILLINOIS, A CORPORATION OF ILLINOIS.

PENCIL.

Application filed March 31, 1922. Serial No. 548,273.

To all whom it may concern:

Be it known that we, CHARLES R. KEERAN and JOHN P. LYNN, both citizens of the United States, residing at Chicago, in the 5 county of Cook and State of Illinois, have invented certain new and useful Improvements in Pencils, of which the following is a specification.

This invention relates to a pencil wherein 10 is combined a propelling mechanism for ejecting a lead as required for use; more particularly our invention is concerned with certain improvements in the propelling mechanism, and in the construction of the 15 pencil body within which the same is contained.

An exemplification of this invention in its preferred form is shown in the accompanying drawing wherein—

20 Figure 1 is a longitudinal section through a pencil whose body is tubular;

Fig. 2 is an enlarged transverse section on line 2—2 of Fig. 1;

25 Fig. 3 is a fragmentary detail in elevation of the upper clip end, looking toward the inner side thereof;

Fig. 4 is a perspective of the eraser and holder therefor;

30 Fig. 5 is a longitudinal section of a pencil whose body is relatively solid as distinguished from the tubular construction shown in Fig. 1; and

Fig. 6 is an enlarged transverse section taken on line 6—6 of Fig. 5.

35 Referring to Fig. 1, the pencil body A therein shown may be formed from tubing, its upper end being adapted to receive a cup-shaped holder 10, which is provided with longitudinal slits 11 so as to form a 40 plurality of spring sections. Oppositely disposed openings 12 are further provided in the cup sides adjacent its bottom, and within a holder of this character is contained an eraser 13 which is secured therein

45 by the pressure resulting from the insertion in the body end of the cup whose walls tend to spring outwardly. Due to the provision of the openings 12 portions of the eraser may bulge therethrough if required so to do by the pressure resulting from assembly in the 50 pencil end. Over the eraser may be removably fitted to the body a cap 14 for purposes of ornamentation.

In abutting relation to the lower end 55 of the pencil body is the cylindrical portion

16 of a pencil tip B which tapers to a point at its lower extremity. As shown the tip is provided interiorly with a sleeve 17 which extends upwardly beyond its cylindrical walls to frictionally engage the body walls and thereby provide a connection of the tip therewith. By preference this extension sleeve is slit as at 18, thereby becoming yieldable to a degree that affords a connection with the body that is both secure and easily 60 rotatable. Arranged centrally within the tip is a tube 19 having its walls provided with spiral threads 20 whose inner diameter is such as to afford a guide for a lead C whose active end 21 is projected through 65 the tip for use. The tube 19 is fixedly carried in the tip so as to rotate therewith when relative rotation takes place between the tip and body.

The tube within the tip extends upwardly 70 within the body for perhaps half the length of the pencil and, in the construction shown, is telescoped within a tube 25 whose walls are spaced from the body walls sufficiently 75 to provide a magazine 26 in the form of an annular chamber for the reception of reserve leads D. Throughout its upper portion 27 the cross section of the body tube is other than round, being elongated, by preference, as shown bent in Fig. 2, so to provide oppositely disposed grooves 28 in which may 80 lie the edges of a head 29 formed on a plunger 30 that is slidably arranged within the body tube 25. In its lower portion the plunger is provided with laterally projecting 85 elements 31 in the nature of teeth or threads which cooperate with the spiral threads 20 of the tube that is carried by the tip. By forming and relating the parts in the manner described, rotation of the tip 90 will effect a longitudinal movement of the plunger whose head co-operates with the grooves 28 to prevent rotation.

The lower end of the magazine 26 is closed by a bushing 35 which is threaded 100 onto the body tube 25. The reserve leads may be inserted or withdrawn through the lower end of the pencil by first removing the pencil tip, and thereafter this bushing. At its upper end the magazine is closed by 105 a plate 36 having a central aperture conforming to the external contour of the upper portion of the body tube, as best indicated in Fig. 2, and owing to its elongated or oval cross section, the tube and the plate are 110

maintained in a non-rotatable relation. The plate is further apertured as at 37 to provide a neck 38 that carries a head 39 which lies in proximity to the body wall. In the 5 region of the head this wall is provided with an opening 40 through which is received the head 41 of a spring clip 42. Immediately above and below the head are lips 43 and 44 adapted to bear against the 10 outer side of the pencil body, and interiorly thereof the clip head is extended to provide slightly tapering flanges 45 and 46 which at their edges 47 and 48 are bent towards each other to embrace the plate head 39 which 15 is adapted to wedge-lock therewith.

In the construction of the pencil herein described, a piece of tubing is cut off to the proper length for the forming of the body A. Thereafter the plate 36 is fitted onto the 20 axial tube 25 and preferably secured thereto as by solder; these two elements as a unit are then slipped into the body with the clip head also inserted therein to lock with the plate head. When this connection is made, 25 both the clip and tube are secured immovably, but may, if necessary for purposes of repair, or otherwise, be disconnected and removed from the pencil. The pencil tip with its parts properly related is thereafter 30 frictionally fitted to the body, so that all the operating elements will be correctly related for service.

A mechanism substantially the same in many respects is shown in Figs. 5 and 6, 35 wherein the pencil body A may be formed of some composition material, or other substance that is relatively solid, as distinguished from the tubular body of Fig. 1. In the construction of Figs. 5 and 6, use is 40 made of a rotatable tip B fitted to the lower body end, and provided with the axial tube 19 in which are formed threads 20 for engaging with the teeth 31 of a plunger 30. The body end engaged by the tip is 45 preferably tapered at its extremity as at 49 and slotted longitudinally as at 50 to provide a compressible structure which bears frictionally against the pencil tip and also against the axial tube 19 therein. The effect 50 of this construction is to enhance the friction resulting from the connection between these parts and thereby provide a more serviceable and stable mounting for the tip upon the pencil end. Within the body is 55 used exactly the same form of axial tube 25 having a cross section which is oval or elongated in its upper region 27. It will be noted, however, that the lower end 51 of this axial tube may terminate short of the 60 pencil tip, and that the magazine for the reserve leads is situated in the upper end of the pencil. By preference we provide on opposite sides of the upper portion 27 of the tube 25 compartments 53 and 54 (see Fig. 65) in each of which may be received two

or more reserve leads D, access to this compartment being afforded only when the eraser holder is withdrawn from the pencil end. To facilitate the mounting of the eraser, we have shown a collar 55 carried 70 at the upper pencil end whose walls are preferably reduced slightly to receive the collar in flush relation therewith.

It will be observed that the expanded or enlarged lower end of the body tube extends above the tube carried by the tip for a distance which is slightly greater than the length of the plunger head. Due to this construction the plunger may freely 75 rotate when in its lowermost position as the head is then no longer engaged within the grooves 28. The result of this is that when the plunger has advanced to its limit there will be no binding of the parts if rotation 80 of the tip is continued.

In the operation of the pencil, the tip is rotated intermittently relative to the body to effect an advancement of the lead for writing purposes. The eraser is normally exposed beyond the end of its cup holder, but when it becomes worn down flush therewith, it may be withdrawn in the following manner. The pencil tip is rotated in a direction normally reverse to that required 90 for advancing the lead until the plunger has been retracted to the position shown in Fig. 1 where its upper end is in abutting relation to the bottom of the eraser cup. Continued rotation of the tip will most likely result in its starting to move off the pencil body, as the eraser holder is fitted to the body more tightly than the tip. With the pencil tip slightly moved down from its normal position, the pencil may then be so manipulated as to press its point 100 against some solid surface with the result that the pressure communicated through the tip and plunger is directed against the bottom of the eraser holder so as to eject the latter from the pencil body. After this has taken place, the holder walls may be distended to permit the insertion of a new eraser, following which the parts are replaced in their normal operating relation. 105 It will be observed also that the edges 22 of the eraser holder are bent inwardly slightly so as to bite into the eraser when the same is mounted in the pencil body, but that when the sides of the holder are distended the eraser may be freely removed.

The present improvements are particularly adaptable to pencils of the kind set forth in the pending application of Charles R. Keeran, Serial No. 512,412, filed November 3, 1921, and two applications of Frank C. Deli, Serial Nos. 444,956 and 504,839, filed, respectively, February 14, 1921, and October 3, 1921. In the present pencil, as in the previous constructions just referred to, new leads may be inserted into the tube 115 120 125 130

that is carried by the tip from either end—from the rear end if the plunger be completely withdrawn therefrom. The advantages which inhere in this invention relate in large measure to the simplicity and ease with which the parts may be constructed and assembled, and to the facility with which they may be taken apart whenever desired for purposes of replacement or otherwise; also to the connection which obtains between the clip and the axial tube wherein is contained the lead propelling mechanism.

We claim:

- 15 1. In a pencil, a body having a tip, the tip and body having telescoping portions and being adapted for relative rotation, a threaded axial tube fixed to the tip, a second axial tube mounted in the body and being open from end to end thereof, the upper portion of the last named tube being non-circular in cross section, while the lower end is of increased diameter and is adapted to receive in telescoping relation the upper 20 end of the threaded axial tube, and a plunger adapted to engage with said threaded tube and having a lateral projection adapted to engage with the non-circular portion of said tube, the enlarged lower end portion of 25 said tube being of such diameter as to permit the projection on the plunger to rotate therein.
- 25 2. In a pencil, the combination of a body and a tip arranged in telescoping, rotatable relation, a threaded lead tube fixed to the tip, a plunger tube secured to the body, the upper portion of the plunger tube being non-circular in cross section, the lower portion of said last named tube being enlarged, 30 a plunger having threads adapted to engage said threaded tube and having a lateral projection adapted to engage with the non-circular portion of the plunger tube, the enlarged portion of said plunger tube at 35 the lower end thereof being adapted to permit the rotation of the projection on the plunger therein, the plunger tube being open from end to end thereof, an eraser seated in the upper end of said body above the open end of said plunger tube and being adapted to be ejected by the reverse movement of said plunger.

the upper portion of the plunger tube being non-circular in cross section, the lower portion of said last named tube being enlarged, a plunger having threads adapted to engage 40 said threaded tube and having a lateral projection adapted to engage with the non-circular portion of the plunger tube, the enlarged portion of said plunger tube at the lower end thereof being adapted to permit the rotation of the projection on the plunger therein, the plunger tube being open from end to end thereof.

3. In a pencil, the combination of a body and a tip arranged in telescoping, rotatable 50 relation, a threaded lead tube fixed to the tip, a plunger tube secured to the body, the upper portion of the plunger tube being non-circular in cross section, the lower portion of said last named tube being enlarged, 55 a plunger having threads adapted to engage said threaded tube and having a lateral projection adapted to engage with the non-circular portion of the plunger tube, the enlarged portion of said plunger tube at 60 the lower end thereof being adapted to permit the rotation of the projection on the plunger therein, the plunger tube being open from end to end thereof, an eraser seated in the upper end of said body above the open 65 end of said plunger tube and being adapted to be ejected by the reverse movement of said plunger.
